(57) **CLAIM**

We claim the ornamental design for a wound dressing, as shown and described.

DESCRIPTION

FIG. 1 is a top view of a first embodiment of a wound dressing;

FIG. 2 is a side view of the first embodiment thereof;

FIG. 3 is an end view of the first embodiment thereof;

FIG. 4 is a top view of a second embodiment of a wound dressing;

FIG. 5 is a side view of the second embodiment thereof;

FIG. 6 is an end view of the second embodiment thereof;

FIG. 7 is a perspective view of the first embodiment showing flexibility thereof; and,

FIG. 8 is a perspective view of the second embodiment showing flexibility thereof.

The portions shown in broken lines in the figures do not form any part of the claimed design.
